(57) **CLAIM**

An ornamental design for a vehicle door handle set, as shown and described.

DESCRIPTION

FIG. 1 is a left side elevational view of one handle of the vehicle door handle set showing our new design, the opposite side is not part of the claimed design;

FIG. 2 is a front elevational view of the vehicle door handle set of FIG. 1;

FIG. 3 is a rear elevational view of the vehicle door handle set of FIG. 1;

FIG. 4 is a top plan view of the vehicle door handle set of FIG. 1;

FIG. 5 is a bottom plan view of the vehicle door handle set of FIG. 1;

FIG. 6 is a perspective view of the vehicle door handle set of FIG. 1;

FIG. 7 is a left side elevational view of one handle of the vehicle door handle set showing our new design, the opposite side is not part of the claimed design;

FIG. 8 is a front elevational view of the vehicle door handle set of FIG. 7;

FIG. 9 is a rear elevational view of the vehicle door handle set of FIG. 7;

FIG. 10 is a top plan view of the vehicle door handle set of FIG. 7;

FIG. 11 is a bottom plan view of the vehicle door handle set of FIG. 7; and,

FIG. 12 is a perspective view of the vehicle door handle set of FIG. 7.
